CLAIM

The ornamental design for a faucet, as shown and described.

DESCRIPTION

In a preferred embodiment, the nature of this product is as a plumbing fixture in the form of a faucet primarily useful for washing various objects.

FIG. 1 is a left, top, front perspective view of a faucet embodying our new design;

FIG. 2 is a left side elevational view thereof, the right side elevational view being a mirror image of the left side elevational view shown;

FIG. 3 is a top plan view thereof;

FIG. 4 is a front elevational view thereof;

FIG. 5 is a rear elevational view thereof; and,

FIG. 6 is a bottom plan view thereof.

The broken line representation of mounting structure in FIG. 6 is for the purpose of illustration only, and forms no part of the claimed design.
